UNITED STATES PATENT OFFICE.

FRANK WALKER, OF LOS ANGELES, CALIFORNIA.

WINDOW-SCREEN.

SPECIFICATION forming part of Letters Patent No. 448,467, dated March 17, 1891.

Application filed June 17, 1889. Serial No. 314,551. (No model.)

To all whom it may concern:

Be it known that I, FRANK WALKER, a citizen of the United States, residing at Los Angeles, in the county of Los Angeles and State 5 of California, have invented certain Improvements in Window-Screens, of which the following is a specification.

The object of my invention is to construct a light and strong window-screen of that class 10 in which a movable tongue is held in a groove cut in one of the side bars of the screen for convenience in placing the screen in or removing it from its position on the window, as more fully set forth hereinafter.

15 In the accompanying drawings, Figure 1 is perspective view of a window-frame, showing my improved screen applied thereto. Fig. 2 is an elevation of the screen, one of the side bars being partially broken away in order to 20 show its construction more clearly. Fig. 3 is a sectional plan view of the screen and window-frame. Fig. 4 is a transverse sectional plan view, on an enlarged scale, of a portion of the screen on the line 1 2, Fig. 2; and Fig. 25 5 is an elevation of the movable tongue detached from the frame.

The window-frame is of ordinary construction, except that the inner sash-guides A are each provided with a shallow narrow groove 30 a, which may be cut by a saw. The screen-frame B is less in width than the space between the guides, and has its opposite side bars C D grooved from end to end, as shown. In one of these grooves is held a fixed tongue 35 b of thin metal, which projects for some distance from the edge of the bar and is adapted to the groove a in one of the sash-guides A. The groove d in the side bar D is of greater depth than that in the side bar C, and seated 40 in said groove is a transversely - movable tongue E, formed of a thin strip of metal. This tongue E is provided with a number of transverse slots e, and the side bar D of the frame is provided with a number of screws g 45 of peculiar form, which extend through such slots and form guides for the tongue, allowing it to move transversely to a limited extent, but permitting no longitudinal movement thereof. Secured in the bottom of the

groove d are bow-springs h, so arranged as to 50 tend to push the movable tongue E from the groove, and to exert their force as evenly as possible along the length of the tongue. When the frame is made, as it preferably is, of very light material, the flanges i, formed 55 by the cutting of the groove d, are necessarily very thin, and would readily break when subjected to any lateral strain if some practical means of bracing and holding them in their relative position were not provided. I 60 accomplish this strengthening by the use of the peculiar form of screw g, (see Fig. 4,) which is of the same diameter throughout its length, terminating in a pointed end, and is threaded from end to end, as shown, so that 65 when passed through the flanges i it holds them equidistant, preventing any relative displacement, and keeps them from binding on the metal tongue E.

In placing the screen in position the edge 70 of the metal tongue E is inserted in one of the grooves a in the side bars A and pushed toward such groove until the tongue is depressed into its groove d a sufficient distance 75 to permit the tongue b to be brought in line with the groove a in the opposite guide-bar A.

Having thus described my invention, I claim and desire to secure by Letters Patent—

1. The combination, in a window-screen, of the side bar D, having a groove extending 80 its entire length and forming two ribs or flanges, a tongue E, adapted to said groove and extending the full length of the screen, said tongue having a series of transverse slots, springs in the groove back of the tongue, and 85 a series of combined guide and tie screws the threads of which engage both ribs or flanges, whereby said ribs are held equidistant and against any lateral strain, substantially as specified. 90

2. The combination, in a window-screen having a fixed tongue on the one side and a longitudinal grooved bar D on the opposite side, said groove extending the full length of the bar, a tongue E, adapted to said groove 95 and provided with a series of transverse slots, springs acting on said tongue, a series of screws rigidly secured to the flanges of the

grooved bar and passing through the trans-
verse slots in the tongue, with window-sash
guides A, having grooves *a*, to which the
tongues are adapted, said screen being so pro-
portioned in respect to the width of the win-
dow-frame that it can be readily removed
therefrom by forcing the spring-tongue into

its groove *d* a sufficient distance to allow the
fixed tongue to clear its groove *a*, substan-
tially as specified.

FRANK WALKER.
